Specification for Design. Patented Jan. 18, 1921.

Application filed May 18, 1920. Serial No. 382,406. Term of patent 14 years.

To all whom it may concern:

Be it known that I, WILLIAM H. HUMPHREY, a citizen of the United States, residing at Youngstown, in the county of Mahoning and State of Ohio, have invented a new, original, and ornamental Design for a Pipe-Union Nipple, of which the following is a specification, reference being had therein to the accompanying drawing.

In the accompanying drawings:

Figure 1 is a perspective view of my new design for a pipe union nipple.

Fig. 2 is a side elevation of the same.

I claim:

The ornamental design for a pipe union nipple, as shown.

In testimony whereof, I hereunto affix my signature.

WILLIAM H. HUMPHREY.
